VAPOR-ELECTRIC DEVICE

Joseph H. Cox, Forest Hills, and Henry C. Myers, Irwin, Pa., assignors to Westinghouse Electric & Manufacturing Company, East Pittsburgh, Pa., a corporation of Pennsylvania

Application August 8, 1942, Serial No. 454,158

2 Claims. (Cl. 250—27.5)

Our invention relates to a vapor-electric device and, particularly, to means for air-cooling vapor-electric valves.

In the operation of vapor-electric converters, a considerable quantity of heat is produced within the vacuum containers of the valves. Many attempts have been made to air-cool such devices, but because of the amount of heat and the nature of the containers, it has heretofore been impractical to air-cool converters passing an appreciable amount of power.

When blowing gaseous fluids, such as air over containers either smooth or with fins, difficulty is experienced because of the layer of dead air immediately adjacent the surface to be cooled. Also, when applying fins or other cooling members, there is an appreciable heat loss because of the joint between the cooling members and the container proper.

According to our invention, we avoid these disadvantages by constructing a container having an inner surface substantially inert to mercury vapor and having an outer surface composed of a metal such as copper which has a high thermal conductivity. In order to readily transfer heat from the exterior surface to a cooling medium, we provide the surface with a large number of integral spines by striking out the portion of the surface of the material into sharp edged spines which readily convey their heat to a surrounding medium.

It is, accordingly, an object of our invention to provide an air-cooled vapor-electric valve.

It is a further object of our invention to provide an improved cooling system for a container.

It is a further object of our invention to provide a container having a plurality of spines for dissipating the temperature to the surrounding medium.

Other objects and advantages of our invention will be apparent from the following detailed description taken in conjunction with the accompanying drawing, in which:

Figure 1 is a vertical elevation partly in section of a vapor-electric valve according to our invention; and

Fig. 2 is a fragmentary section of a side wall of the container showing the arrangement of the spines.

Fig. 3 is a perspective view of a fragment of the surface showing the spines in detail.

In the illustrated embodiment of our invention according to Fig. 1, the vapor-electric valve 10 comprises a cathode 11 of vaporizable reconstructing material, such as mercury, contained in the bottom of an evacuated container 12. Co-operating with the cathode 11 is a suitable an-

ode 13, preferably of graphite, maintained in insulated relation to the container walls. A suitable exciting device such as a make-alive electrode is supported by an insulated lead-in stem 14 extending through the side of the container 12. The inner portion 15 of the container 12 is composed of a metal, such as iron, which is substantially inert to mercury or mercury vapor. The exterior surface 16 of the container 12 is preferably constructed of a metal which has a high thermal conductivity such as copper.

While the inner and outer portions of the wall may be connected together in any suitable manner, I prefer to solder or braze the exterior surface 16 onto the inner container wall 15. The exterior surface 16 of the heat-conducting metal is provided with a plurality of spines 17 in the order of approximately 50 spines per square inch of surface. The spines 17 may be struck up either from the flat sheet before it is attached to the converter or the sheet may be attached and the spines struck up after attaching to the container. In any event, the spines 17 are of substantially small cross-sectional area having sharp edges and integrally attached to the base metal sheet. A cooling fluid, such as air, is circulated about the container 12 by any device such as a fan 20. The air flowing over the spines 17 comes in intimate contact with the surface thereof, and because of the sharp edges of the spines, heat is readily transferred from the spines 17 to the moving fluid.

While for purposes of illustration we have shown and described a specific embodiment of our invention, it is apparent that changes and modifications may be made therein without departing from the true spirit of our invention or the scope of the appended claims.

We claim as our invention:

1. A cooling system for a mercury vapor arc discharge device comprising a container wall having an inner surface substantially inert to mercury, an outer surface having good heat conducting characteristics, said outer surface having a plurality of integral spines distributed thereon of the order of fifty per square inch of surface.

2. A vapor-arc discharge device comprising a ferrous container, an anode and a vaporizable cathode in said container, cooling means for said container including a sheet of metal of high thermal conductivity applied in good thermal contact with said container, and integral spines struck up from said sheet.

JOSEPH H. COX.
HENRY C. MYERS.
